UNITED STATES PATENT OFFICE.

MILFRED L. GREENSTREET, OF OWENSVILLE, MISSOURI.

FLUE-STOPPER.

SPECIFICATION forming part of Letters Patent No. 729,328, dated May 26, 1903.

Application filed September 4, 1902. Serial No. 122,091. (No model.)

To all whom it may concern:

Be it known that I, MILFRED L. GREENSTREET, a citizen of the United States, and a resident of Owensville, in the county of Gasconade and State of Missouri, have invented a new and Improved Flue-Stopper, of which the following is a full, clear, and exact description.

This invention relates to a device which is adapted to be placed around a flue so as to form when the stovepipe is removed a stopper completely closing the flue and which when the stovepipe is in place may be adjusted to fit tightly around the pipe irrespective of the size thereof, provided, of course, that the size of the pipe is not beyond the maximum capacity of the device.

The invention comprises a collar with a number of pivoted sector-like sections arranged on its inner side, so that when these sections are thrown out into inactive position they lie back of the collar and do not appear, said sections being of such peculiar construction and relative arrangement that they may be readily moved inward to fit tightly around a stovepipe or to extend completely over and close the central opening of the collar.

This specification is a specific description of one form of the invention, while the claim defines the actual scope thereof.

Reference is to be had to the accompanying drawings, forming a part of this specification, in which similar characters of reference indicate corresponding parts in all the figures.

Figure 1 is a front view of the invention, showing by dotted lines the folding sections moved partly inward to fit around and cover a relatively small stovepipe. Fig. 2 is a vertical section taken on the line 2-2 of Fig. 1, and Fig. 3 is an inside view of the device.

The collar is formed, preferably, of sheet metal and comprises a main portion a , the outer periphery of which is formed with an inward and thence outwardly extending flange a' , which is adapted to be fastened by tacks or like devices to the wall in which the flue-opening b is formed. Reference particularly to Fig. 2 will show that this construction of the collar provides a cavity between the collar and the wall, and in this cavity are ar-

ranged the above-referred-to swinging sector-like sections. Said sections are formed of sheet metal, and each comprises an inner edge c , curved concentrically to the inner periphery of the collar a , an outer edge c' , curved eccentrically to the edge c , a pointed end c^2 , and a wide end c^3 opposite the end c^2 . These sections have therefore essentially the form of a curved wedge. The folding sections are pivoted to the collar a at the inner corners of their wide ends c^3 , as indicated at the points d , and each section is formed on its edge c with a tongue c^4 , said tongues extending outward and adapted to strike against the inner edge of the collar a when the folding sections are moved outward, so as to limit the outward movement of the sections and so, also, as to furnish finger-grips facilitating moving the sections inward.

When the folding sections of the device are thrown outward, they lie wholly back of the collar and nothing appears at the front excepting the tongues or studs c^4 . To move the sections inward either to adjust them around a stovepipe or to completely close the interior of the collar, it is only necessary to grasp the studs c^4 and move the swinging sections toward the center of the device. Fig. 1 by dotted lines shows these sections moved partly inward. In this view the dotted lines e represent the stovepipe.

Various changes in the form, proportions, and minor details of my invention may be resorted to without departing from the spirit and scope thereof. Hence I consider myself entitled to all such variations as may lie within the scope of my claim.

Having thus described my invention, I claim as new and desire to secure by Letters Patent—

The combination of a collar comprising a body portion, and a flange projecting inward from the outer edge thereof, said flange being adapted to be connected to the supporting surface, whereby to sustain the body of the collar projecting forward from said surface, a number of swinging segmental sections pivoted at the inner side of the body of the collar at their widened ends, and capable of moving outward behind the body of the collar so

as to be concealed, and a tongue or stud attached to the inner edge of each section, said tongues or studs being projected forwardly through the opening in the collar at the front 5 side thereof, the construction being such that the outward movement of the sections will be limited by said studs, substantially as set forth.

In testimony whereof I have signed my name to this specification in the presence of 10 two subscribing witnesses.

MILFRED L. GREENSTREET.
